UNITED STATES PATENT OFFICE.

LEVI HICKS, OF HOLLAND, MICHIGAN, ASSIGNOR TO INVINCIBLE GRAIN CLEANER-COMPANY, OF SILVER CREEK, NEW YORK.

GRAIN-SCOURING APPLIANCE.

1,221,855.

Specification of Letters Patent. Patented Apr. 10, 1917.

Application filed April 21, 1915. Serial No. 22,951.

To all whom it may concern:

Be it known that I, LEVI HICKS, a citizen of the United States of America, residing at Holland, in the county of Ottawa and State 5 of Michigan, have invented certain new and useful Improvements in Grain-Scouring Appliances; and I do hereby declare the following to be a full, clear, and exact description of the invention, such as will enable others skilled in the art to which it 10 appertains to make and use the same.

This invention relates to grain scouring devices, and it is the object and purpose thereof to provide improvements in the casing and in the rotating beating bars of a grain scouring machine whereby the grain taken into the machine will be cleaned and more thoroughly scoured to remove impurities from the grain than heretofore. It is 15 a further object and purpose of the invention to fashion the inner surface of the casing and the surfaces of the beating bars with various roughened depressions and abrasive projections respectively such that 20 when the grain is acted upon by the bars the surface of each kernel of grain will be scoured removing any and all impurities which may have collected on the outside of 25 the kernels. The improvements by which 30 these ends are attained are shown in the accompanying drawings, in which;

Figure 1 is a front elevation, with the frame removed and with parts of the scouring casing omitted, of a scouring machine to 35 which my improvements are applied.

Fig. 2 is a front elevation of one of the curved plates, a plurality of which are used to make the scouring casing.

Fig. 3 is a perspective view of the preferred form of scouring plate.

Fig. 4 is a transverse section taken through the plate shown in Fig. 3.

Fig. 5 is a perspective view of one of the improved beating bars used; and

Fig. 6 is an enlarged fragmentary sectional view through one of the depressions formed in the plate shown in Fig. 3.

Like reference characters refer to like parts throughout the several views of the 50 drawings.

A well known type of scouring machine is shown in Fig. 1 and comprises a frame 1 in which is mounted a horizontal shaft 2 adapted to be driven through the pulley 3 attached at one end thereof. Adjacent its opposite end a fan 4 is secured to the shaft and rotates in the fan box 5 shown, which box is directly connected with the scouring casing 6 supported in the frame between the fan in the drive pulley. 55

In construction the scouring casing is a cylinder made up of a plurality of plates 7 and the ends of the cylinder are closed by plates 8 and 9 through which the shaft 2 passes. The entrance to the casing through 60 which the grain is passed is indicated at 10 being located adjacent the end of the casing which is nearest the fan box 5. The grain is passed from the scouring casing through an opening 11 in the other end 65 plate 9, passing into an outlet spout 12 as shown in Fig. 1.

Each of the curved plates 7 is provided with lugs 13 for attachment to similar lugs on adjacent plates to form the cylindrical 70 casing, bolts 14 extending through these lugs to secure the plates together. All of the plates are provided with a large number of transverse slots 15 as shown.

Scouring machines of the construction 80 thus far described are old and well known. My improvement in the casing construction consists in forming a plurality of depressions on the inner surfaces of the plates 7 as shown at 16, which are roughened 85 slightly so that as the grain is thrown against the surfaces a slight abrasive action against the outer surface of the kernels of the grain takes place, rubbing or scouring off any dirt, smut or like impurities that 90 may be on the outer surface of the grain and more completely scouring it than heretofore. Instead of the depression 16 it may be advisable to make a plurality of elongated depressions or flutes as shown at 17 95 in Fig. 2. It will, however, be noted that in both cases the depressions have angular surfaces, substantially against which the grain will be thrown so that it will be naturally turned back again after it is thrown 100

into the depressions, whether of the form shown in Fig. 3 or that shown in Fig. 2. Other modifications may be resorted to. For instance, the location of the depressions 5 or flutes 17 need not be parallel to the length of the plate 7 but may lie at any desired angle to the length. In all cases, however, the surfaces of depressions 16 and 17 are slightly roughened.

10 To complete the scouring machine a pair of spaced apart hubs 18 are connected to the shaft 2 adjacent each of the ends 8 and 9 of casing 6 and have arms 19 extending radially therefrom. Each pair of arms 19 15 serves as a support for a beating bar 20 which is connected by any suitable connection such as bolts extending through the slots 21 adjacent the ends of the bars. These bars lie parallel to the length of the scouring casing with their outer edges spaced a short distance from the inner surface of the casing. On each edge the bar is formed with a plurality of ribs 22 while both sides of the bar have a plurality of projections 23 extending outwardly therefrom. It will be noted that the bar 5 has the appearance of a rasp and as a matter of practice an ordinary rasp may be used with good results as the beating bar in the embodiment of my invention. Heretofore these bars have been plain but my improvement in the bar consists in the roughening of the sides and edges of the bar to form projections and surfaces that will operate with considerable severity 35 on the outer surface of the kernels of the grain. It has been found in practical experience that the projections 23 on the bar will even enter the creases in the kernels of grain such as wheat or rye, and remove any 40 dirt that may have become fixed therein.

With a construction as thus described the advantages will be readily apparent. Grain entering through the entrance 10 is acted upon by the bars 20 which are rotated very 45 rapidly, sometimes at the rate of seven hundred revolutions per minute. The rotation has the effect of throwing the grain outwardly against the inner surface of the scouring casing and as the grain passes across the face of the beating bar it is rasped and scoured by the rough surface thereof as will be readily apparent. As it leaves the beating bar and is thrown against the inner surface of the casing it is carried into a depression 16 or 17 and is further scoured as it strikes against the roughened surfaces in the depression, being again turned outwardly by reason of the incline at which these surfaces are cut so as to come in contact again with the beating bar. Also the edges 22 of the bars act against grain which may be between the bars and the casing. The fan serves to draw air through the slots

15 and through the passageway into the fan casing. A large amount of the lighter impurities in the form of dust in this manner are carried out of the scouring casing and are discharged by the fan, while the heavier scourings pass through the slots 15 and are discharged through the funnel 24 shown in Fig. 1.

These improvements in scouring machines make it possible to clean and place in condition for milling, grain which heretofore has been practically useless for milling purposes. The abrasive action of the beating bars in connection with the scouring action of the roughened surfaces of the depressions cleans the kernels of grain much better and more satisfactorily than heretofore. Grain 80 entering the scouring casing in a dirty and foul condition is discharged through the outlet 12 in a perfectly clean and bright condition ready for milling purposes.

Slight modifications in detail may be resorted to without departing from my invention which is defined in the appended claims and all modifications in construction falling within the scope of said claims are to be considered as comprehended within my invention.

I claim:

1. In a grain scouring machine, a scouring casing having a plurality of depressions the sides of which are roughened and lie at an angle to the inner surface of the casing, a shaft extending through the casing, arms projecting radially from the shaft, and beating bars secured at the ends of the arms, said bars being comparatively wide and thin, having sides and edges formed with abrading projections and positioned so that the width of a bar is at right angles to the inner surface of the casing, substantially as described.

2. In a grain scouring machine, a scouring casing having a plurality of depressions formed on its inner surface, the surfaces at the depressions being roughened, comparatively wide and thin, beating bars positioned lengthwise of the casing and adjacent the inner surface thereof and extending inwardly therefrom, and abrading projections formed on the sides and edges of said bars, said projections on the side being located diagonally across the surface of said sides, substantially as described.

3. In a grain scouring machine, a scouring casing having a plurality of conical depressions formed on the inner surface thereof, the surfaces at the depressions being roughened, a plurality of comparatively wide and thin beating bars, each having abrading projections on the sides and edges thereof, positioned lengthwise of the casing and adjacent the inner surface thereof, the edges of

said bars being located directly opposite the inner surface of the casing and the sides of the bars at right angles thereto, and means to rotate said bars, substantially as de-
5 scribed.

4. In a grain scouring machine, a scouring casing having a plurality of depressions formed on its inner surface, the sides of the depressions being roughened and formed at

an obtuse angle to the inner surface of the 10 casing, substantially as described.

In testimony whereof I affix my signature in presence of two witnesses.

LEVI HICKS.
